SELF-CONTAINED AIR CONDITIONING UNIT INSTALLATIONS

William L. McGrath and Francis D. Stevens, Syracuse, N.Y., assignors to Carrier Corporation, Syracuse, N.Y., a corporation of Delaware

Application January 5, 1954, Serial No. 402,364

9 Claims. (Cl. 98—94)

This invention relates to self-contained air conditioning units, and more particularly, to mechanism for maintaining the unit in place within a window frame or other opening within a building.

The chief object of the present invention is to provide support members for a self-contained air conditioning unit installed within a building opening such as a window frame.

An object of the invention is to provide support means for a self-contained air conditioning unit installed within a window frame which permits the unit to be installed in such a manner that any desired length of the unit may protrude from the window frame.

A further object is to provide support means for a window unit placed within a window frame, which includes an adjustable cradle or track member for supporting the portion of the unit protruding from the window frame. Other objects of the invention will be readily perceived from the following description.

This invention relates to a cradle member for supporting a self-contained air conditioning unit in a building opening which comprises, in combination, a support member including two horizontally extending arms, each arm having a longitudinally extending flange adapted to be secured to a portion of the window frame, a support for the unit and a gasket receiving recess placed between the flange and the support; a second support member including two horizontally extending arms and a connecting member, and means for removably attaching the second member to the first member.

This invention further relates to a self-contained air conditioning unit placed within a building opening in combination with support means for the unit which comprises a cradle member including two arms protruding exteriorly of the opening, each arm terminating in a horizontally extending flange secured to a portion of the opening wall, each arm including a support for the unit and having a gasket receiving recess placed between the support and the flange; and a second cradle member engaging the first cradle member and extending therefrom to increase the length of the unit support; the cradle members being adapted to be connected at various points whereby the length of the support may be adjusted in accordance with the portion of the unit protruding from the opening; said second cradle member having a flange substantially perpendicular thereto extending about its rear and at least a portion of its side receiving the unit therein to prevent sideward and outward movement of the unit.

The attached drawings illustrate a preferred embodiment of the invention, in which

Figure 1 is a view in elevation of the self-contained air conditioning unit in place;

Figure 2 is an exploded view of the elements of the support;

Figure 3 is an isometric view showing the cradle members of the support installed at the building opening; 70

Figure 4 is a sectional view showing the self-contained

2

air conditioning unit in place within the window opening; Figure 5 is a sectional view illustrating the manner of installation of the wing panels;

Figure 6 is an isometric view of the picture frame gasket;

Figure 7 is a sectional view of a modified gasket; and

Figure 8 is a view in elevation illustrating the modified gasket in place about the air conditioning unit.

Referring to the attached drawings, there is shown a 10 self-contained air conditioning unit 2 supported in place within a building opening such as a window frame 3. It will be observed that substantially the complete length of the unit 2 extends exteriorly of the frame 3. The casing of the unit is box-like to permit the unit to be placed in any desired position in the building opening.

The air conditioning unit is held in place within the opening by means of a support designated generally at 4. Support 4 prevents outward and sideward movement of the unit 2 when it is installed in desired position.

20 Support 4 includes a cradle or track member 5. Cradle 5 includes two horizontally extending arms 6, each arm including a support portion 7, a flange 8 extending substantially perpendicular to the support portion at one side thereof, and serving to prevent sideward movement of the unit when it is installed, and a second flange 9 extending downward from the opposite side of support 7 in a substantially perpendicular direction. Flange 9 has a plurality of openings 10 formed therein for a purpose hereinafter described. Each arm 6 has a horizontally extending flange member 11 attached thereto and adapted to be secured to the stool 12 of the window frame.

25 The support includes a second cradle having two horizontally extending arms 13, each arm including a support 14, a flange 15 extending downward from the support 14 in a substantially perpendicular direction, and a second flange 16 extending upward at the opposite side of support 14 in a substantially perpendicular direction. Flanges 16 of the arms 13 are connected by a member 17 which forms, in effect, a continuation of flanges 16. Openings 17' are provided in flanges 15 for a purpose hereinafter described. The arms 13 are provided with members 18 adapted to cooperate with leveling means 19. In this construction, the leveling means are in effect attached to the unit so that an unsafe installation 30 cannot be made.

35 When the support or cradle is placed in position at the window opening, supports 14 of arms 13 rest on supports 7 of arms 6. The arms 6 and 13 are attached to each other by fastening means 20. Since a plurality of openings are provided in the flanges 9 and 15, it will be appreciated that various openings may be aligned with each other to permit the cradle to be adjusted in length, depending upon the portion of the unit protruding exteriorly of the opening.

40 45 Gasket receiving recesses 21 are formed in the cradle between arms 6 and flange members 11 for a purpose hereinafter described. To strength the cradle member and to provide support for a gasket in recess 21, a tie angle 22 is provided connecting the arms 6; this tie angle forms the rear wall of the gasket recess 21.

50 55 Considering the installation of the self-contained air conditioning unit, assuming the cradle 5 has been installed in desired position, extending from the window frame with the flange members 11 attached to the stool 12 of the window frame, the air conditioning unit 2 is supported on the cradle 5 with a desired length of the unit protruding exteriorly of the window frame. It will be appreciated any desired length of the air conditioning unit may extend from the opening since cradle 5 is adjustable to accommodate any desired portion of the air conditioning unit exteriorly of the window opening. The flanges

8 and 16 of the arms 6 and 13 of cradle 5 prevent sideward movement of the unit when it is in desired position. The connecting member 17 prevents further outward movement of the unit.

A "picture frame" ring gasket 23 (refer to Figure 6) is disposed about unit 2. Ring gasket 23 may be disposed at any desired place longitudinally of the unit. Gasket 23 preferably includes a slot 24 for a purpose hereinafter described. The gasket 23 fits within recess 21 to seal the lower portion of the unit and is compressed by the weight of unit 2, thus preventing air entering the interior of the building structure between the stool of the window frame and the bottom of the self-contained air conditioning unit.

After the gasket has been disposed about the unit and the unit placed in desired position on the cradle, wing panels 25 and 26 are placed in position on opposite sides of the unit to close the space between the sides of the window frame and the unit. The edge of the wing panel fits within the slot 24 of the ring gasket 23. Suitable spacing and support members 27 are provided to hold the wing panels in place adjacent to the window frame.

If desired, a key member 28, as shown in Figure 4, is inserted in the slot 24 of gasket 23 above the top of unit 2. A rubber seal strip 29 or gasket has a protruding portion adapted to fit against the inner side of the window and a slot 30 therein adapted to receive key 28, if desired, and the upper edges of wing panels 25 and 26. The window is then lowered to compress the seal strip, thus securely sealing the space between the window and the unit and its wing panels.

As shown in Figures 7 and 8, the picture frame gasket and the seal strip may be formed integrally to provide sealing gasket 50. The upper portion of gasket 50 terminates in a tip-like portion 51 adapted to fit against the inner edge of the window when the unit and gasket are in place in the installation. The slots (not shown) are retained to receive the edges of the wing panels 25, 26. Gasket portions 52, 53 fit over the upper edges of the wing panels 25, 26 receiving such edges in slots 54 therein. Any suitable form of joint 55 may be provided between gasket 50 and cooperating gasket portions 52, 53. It will be appreciated this construction obviates the rubber strip and key construction.

Preferably, stop brackets 31 are provided to prevent inward movement of the unit 2 when it is disposed in position. The flange members 11 of arms 6 of cradle 5 are provided with embossed portions 32 extending from the edges thereof so as to provide space between the flanges and the stool 12 of the window frame. Brackets 31 include a horizontally extending flange 33 adapted to fit within the space between portions 32 and the stool, and an upwardly extending flange 34 adapted to be attached to the unit 2.

Preferably, the unit 2 is disposed in position in such manner that it tilts slightly toward the exterior of the building. This aids in removing the condensate from the evaporator section of the unit to the condenser section of the unit. Leveling means 19 permit the cradle 5 to be adjusted so as to provide the desired pitch.

The present invention provides an air conditioning unit installation which may be made rapidly and economically. The installation prevents seepage of exterior air through the building opening about the installed unit. The present invention provides secure support regardless of the length of the unit extending without the building structure. If desired, exterior strap hangers or braces may additionally support the unit if the greater part of the unit is supported without the building. If the greater part of the unit is supported within the building, leg supports may be used. The hanger or brace construction permits a satisfactory installation to be obtained when the wall is so thin that it is undesirable to employ standard leveling screws. Any movement of the unit, when it is installed in desired position, is prevented by the

support provided by the present invention. The installation may be made readily by unskilled workmen. A particular advantage of the construction rests in the fact that the unit can be pulled through the gasket; there is no requirement that the unit be placed in any particular position. A particular feature of this installation resides in the fact that seepage of outside air around the unit is prevented eliminating drafts and preventing sweating under summer conditions as well as maintaining capacity of the unit. The unit need not be removed during winter conditions for the seal prevents seepage or leakage of air through the opening.

While we have described a preferred embodiment of the invention, it will be understood the invention is not limited thereto since it may be otherwise embodied within the scope of the following claims.

We claim:

1. In combination of a self-contained air conditioning unit placed within a building opening, support means for the unit comprising two arms protruding exteriorly of the opening, each arm terminating in a horizontally extending flange secured to a portion of the opening wall, each arm including a substantially horizontally extending first portion on which the unit rests, an upwardly extending second portion at one side of the first portion and a downwardly extending third portion at the opposite side of the first portion, each of said arms having a gasket receiving recess between the first portion and the flange, and second support means cooperating with the first support means to support the unit, the second support means extending from the first support means, said second means comprising two spaced arms and a connecting member, each arm including a substantially horizontally extending first portion on which the unit rests, an upwardly extending second portion at one side of the first portion and a downwardly extending third portion at the opposite side of the first portion, said second support member having a flange connecting the ends of the arms and cooperating with the upwardly extending second portions thereof to prevent sideward and outward movement of the unit, means to connect the first and second support members to each other, said first and second support members being capable of connection at various points whereby the length of the arms may be adjusted in accordance with the portion of the unit protruding from the opening, and means for securing the support means in desired position to support the unit.

2. The combination according to claim 1 in which a gasket extending about the unit is placed in the recess and is compressed therein by the unit forming a seal between the unit and the window frame.

3. The combination according to claim 2 in which the gasket is slotted to receive the edges of a key member and wing panels.

4. In a mounting arrangement for supporting a self-contained air conditioning unit in a window opening, the combination of a support member including two horizontally extending arms, each arm having a horizontally extending flange adapted to be secured to the stool of the window frame, a support portion for the unit integral with the flange having a gasket receiving recess therein placed between the flange and the support, a second support member including two horizontally extending arms and a connecting member connecting the arms, and means for removably attaching the arms of the second member to the arms of the first member.

5. A mounting arrangement according to claim 4 in which the arms are provided with flanges extending substantially perpendicular of the support portion to prevent sideward movement of a supported unit.

6. A mounting arrangement according to claim 5 in which the connecting member forms a continuation of the flanges to prevent outward movement of a supported unit.

7. A mounting arrangement according to claim 6 in

which the arms of the first support member are connected by a tie angle.

8. A mounting arrangement according to claim 7 in which the horizontally extending flanges are provided at their outer edges with embossed portions to receive therein flanges of stop brackets.

9. In a mounting arrangement for supporting a self-contained air conditioning unit in a window opening, the combination of a support member including two horizontally extending arms, a tie member connecting the arms, each arm including a support portion for the unit, a flange extending substantially perpendicular to the support portion at one side thereof, and a second flange extending substantially perpendicular to the support portion at the opposite side thereof, horizontally extending flange members integral with the support portions of the arms adapted to be secured to the stool of the window frame, each support portion having a gasket receiving recess therein placed between the horizontally extending flange member and the support portion of the arms, a second support member including two horizontally extending arms, a connecting member connecting said arms of the second support member, each arm including a support portion for the unit, a flange extending substantially perpendicular to the support portion 25

at one side thereof, and a second flange extending substantially perpendicular to the support portion at the opposite side thereof, the connecting member extending substantially perpendicular to the support portion and forming, in effect, a continuation of the flanges to prevent outward movement of a supported unit, and means for removably attaching the second flanges of adjacent arms, the horizontally extending stool flange members having embossed portions at their outer edges to receive stop brackets, and stop brackets fitting between the embossed portions and the stool and attached to the unit.
